UNITED STATES PATENT OFFICE.

LEVI WOLFORD HAMILTON, OF PORTLAND, TENNESSEE.

ACETYLENE-GENERATOR.

1,365,913.

Specification of Letters Patent. Patented Jan. 18, 1921.

Application filed March 12, 1917. Serial No. 154,262.

To all whom it may concern:

Be it known that I, LEVI W. HAMILTON, a citizen of the United States, residing at Portland, in the county of Sumner and 5 State of Tennessee, have invented a new and useful Acetylene-Generator, of which the following is a specification.

This invention has reference to acetylene generators, and its object is to provide an 10 acetylene generator of simple construction which will avoid some objections which have been found to exist in acetylene generators as heretofore constructed.

In accordance with the invention two 15 tanks are provided, one inclosing a carbid chamber or receptacle with an underlying water chamber, and the other tank containing a gas bell, the tanks being connected to suitable piping for conducting the generated acetylene gas from the generating 20 chamber to the storage chamber represented by the gas bell.

The carbid chamber is provided with an inverted conical bottom portion in which is 25 located a conical hood overlying an opening through the smaller end of the conical bottom, and in such opening there is lodged a conical valve so arranged that the valve is partly within and partly below the conical 30 bottom and extends at all times through the outlet of the carbid chamber. The valve is of such length that while its large end is below the carbid chamber and is too large to enter the carbid chamber through the 35 outlet thereof, the small end is within the conical hood overlying the outlet end of the carbid chamber. The hood has a hollow stem rising from it and through this hollow stem projects a valve stem carrying the 40 conical valve, the stem being in turn carried by a rock arm on a shaft extending to the exterior of the chamber in which the carbid chamber is lodged and there provided with an arm carrying an adjustable weight, 45 which arm is also connected to the gas bell so as to be actuated thereby.

The invention includes other features which will be described hereinafter.

The invention will be best understood 50 from a consideration of the following detailed description, taken in connection with the accompanying drawings forming part of this specification, with the further understanding that while the drawings show a 55 practical form of the invention, the latter is not confined to any strict conformity with

the showing of the drawings, but may be changed and modified so long as such changes and modifications come within the scope of the appended claim. 60

In the drawings:

Figure 1 is a plan view of the acetylene generator with the top of the carbid chamber removed.

Fig. 2 is a vertical cross sectional view of 65 the apparatus with certain parts shown in elevation.

Fig. 3 is a section on the line 3-3 of Fig. 1.

Referring to the drawings there is shown 70 a casing 1 from which rises another casing 2 constituting a continuation of the casing 1, and which may be of less diameter than the casing 1. The two casings are in free communication where they join, and the 75 casing 2 is provided with a removable cover 3. Within the casing 2 near the upper end thereof is a carbid chamber 4 which may be in the form of a cylinder supported by brackets 5 on the interior of the casing 2. 80 The carbid chamber 4 has a bottom 6 of inverted frusto-conical form having an opening 7 through its smaller lower end, through which opening carbid may fall and enter the chamber 1. When the parts are ready 85 for operation the chamber 1 contains a suitable quantity of water, indicated in Fig. 2 at 8, so that the carbid is acted upon by the water to produce acetylene gas in the usual way. In order to fill the chamber 1 with 90 water a screw plug 9 is provided, thus permitting access to the chamber 1 and providing a means for closing the chamber against escape of the generated gas to the atmosphere. 95

Extending across the interior of the carbid chamber 4 are spaced strips 10 supporting an upright tube 11, which at the lower end, is expanded into or carries a cone-shaped shield or deflector 12 entering the 100 conical bottom 6 in overriding relation to the opening 7 and approaching, but at the edges spaced from, the walls of the bottom 6. The width of the cone 12 at its other lower end is greater than the width of the 105 opening 7, so that the weight of a mass of calcium carbid in the carbid receptacle is in most part supported by the cone 12, thus relieving the bottom 6 from such weight to a marked extent. 110

Extending through the opening 7 is a conical valve 13, which valve may be of hol-

low construction, and has its larger or basic end below the bottom 6 and of greater diameter than the opening 7. The apex end of the cone valve 13 is located high enough to enter the cone shield 12, and the valve is carried by a valve stem 14 extending through the tube 11 to a point above the latter, where it is carried by a rock arm 15 fast on a rock shaft 16 having journal bearings 17, 18 in opposite sides of the extension 2 of the casing 1. The shaft 16 passes through the chamber 4 as seen in Fig. 1 and has one end extended through the exterior of the casing 2 and there carries an arm 19 with an adjustable weight 20 on one end.

The cover 3 is secured to the casing 2 by bolts 21 or otherwise and carries a removable plug 22, whereby access may be had to the interior of the carbid container for introducing carbid thereinto.

Entering the casing 1 is a tube 23 through which there extends a rotatable rod 24 carrying a pivoted plate 25 within the casing 1 at the bottom thereof, while the other or upper end of the rod 24 has a handle 26, whereby the rod may be rotated to agitate sludge accumulating on the bottom of the casing 1. A removable plug 27 is provided near the bottom of the casing 1 for drawing off the sludge after agitation.

Adjacent to the casing 1 is another casing 28 having an open top and containing a gas bell 29, the casing 28 being supplied with a suitable quantity of water, indicated at 30, to provide a water seal for the gas bell in the usual manner. The bell 29 is provided with brackets 31 traveling along the upright members of an arch frame 32 so that the bell may rise and fall and be guided by the arch 32. In order to support the arch other brackets 33, 34, respectively, are made fast to the exterior of the casing 28 and receive the lower ends of the legs of the arch 32 to support the latter. One of the brackets 31 on the bell 29 has a chain 35 fast at one end thereto, while the other end of the chain is provided with a hook 36 engaging that end of the arm 19 remote from the weight 20, so that the weight 20 will drop when the bell 29 rises and will be pulled up when the bell 29 drops.

The space in the casing 2 below the carbid chamber and that portion of the chamber 1 above the level of water therein constitutes a gas chamber. Leading from the casing 2 is a pipe 37 connected to another pipe 38, which in turn is connected to still another pipe 39 leading into the casing 28 near the bottom thereof, so as to be below the lower limit of travel of the bell 29. The pipe 39 connects to a riser 40 continued to a high point in the bell 29, and then having a downwardly extended leg 41 terminating at a considerable distance below the level of the water 30 in the casing 28 in a T branch 42,

whereby gas flowing through the pipes 37, 38 and 39 rises in the pipe 40, and then is directed downwardly through the pipe 41 into the branch 42 where it is directed in a plurality of streams into the water 30 at a relatively low point therein so as to rise through the water into the gas bell and be washed by such water.

Opening into the gas bell 29 at a high point is another pipe 43 continued downwardly to near the bottom of the casing 28 where it is connected to another pipe 44 leading through the casing 28 to the exterior thereof, and there connected to a service pipe 45 through a controlling valve 46 and a filter 47. The pipes 39 and 44 are connected together for mutual support by a plug 48 screwed fast to the two pipes, but preventing communication between them.

When the generator is first placed in commission the chain 35 is unhooked from the arm 19, whereupon the weight 20 rocks the arm 19 in a direction to raise the valve 13 into closing position with respect to the opening 7, the weight being sufficient to hold the valve in such closed position against any tendency of the carbid to force it open. Water is placed in both chambers or casings 1 and 28 and carbid is introduced into the carbid container 4 through the opening normally closed by the plug 22, which plug is afterward replaced.

With the parts thus in readiness the bell 29 is raised and the chain end of arm 19 lowered until the chain 35 can be hooked on to the arm 19 and by rocking the arm 19 a few times at suitable intervals carbid is discharged into the water 8 and gas is generated and accumulates in the bell 29 until the latter has risen sufficiently to permit the weight 20 to drop, and thereby close the valve 13. Because of the tapering shape of the valve 13 within the carbid chamber with the taper being in a direction and of an extent to enter the shield 12, all liability of the valve being caught in the open position by a piece of carbid large enough to hold it in such position is avoided. Where a relatively small rod extends through the discharge opening of the carbid chamber it frequently occurs that a piece of carbid of larger size than usual will jam the rod and hold the valve open, so that the smaller pieces of carbid will continue to feed without control. The result is that the generator becomes overcharged with gas and both the carbid and the gas are wasted. This occurs sometimes even when a shield like the shield 12 overrides the valve. Again, when the valve tapers toward the discharge opening of the carbid chamber pieces of carbid will lodge.

With the acetylene generator described imperfect feed has never been experienced, although many generators have been em-

ployed through some years of testing. This certainty of feed is ascribed to the fact that the valve is partly within and partly without the carbid holder and is larger below the discharge opening than it is above the discharge opening, the valve always rising above any carbid which may engage it, and also rising so high in the carbid chamber at all times that the upper end of the valve is 10 within the protecting hood or deflector overriding the discharge opening of the carbid container.

The comparatively small valve rod is entirely free from contact with carbid at any 15 time.

The carbid receptacle 4 being a separate structure from the casing member 2 is removable therefrom when the cover 3 is removed. In order to hold the carbid receptacle in proper relation so that the shaft 16 may be removed from its bearings and replaced therein, since the shaft extends through the carbid receptacle, the cover 3 is provided with a depending holding member 20 49 provided at its lower end with entering slots 50 so positioned as to straddle the upper guide strips 10. This insures the proper lo-

cation of the carbid receptacle on the brackets 5 to readily receive the shaft 16.

What is claimed is:—

In an acetylene generator, a generating chamber provided with a removable carbid receptacle having a conical deflector within the receptacle and located over the outlet thereof, said deflector being provided with an axial tubular extension, supporting strips connected to opposite sides of the carbid receptacle and embracing the tubular extension, a cover for the generating chamber, a valve for the outlet of the carbid receptacle, an operating shaft for the valve extending to the exterior of the carbid receptacle, and a depending member on the cover having slots for receiving a guide strip to hold the receptacle in fixed position in the generating chamber when placed therein.

In testimony that I claim the foregoing as my own, I have hereto affixed my signature in the presence of two witnesses.

LEVI WOLFORD HAMILTON.
